UNITED STATES PATENT OFFICE.

CYRUS L. BUNDY, OF EAST ORANGE, AND WILLIAM GRANT, OF PASSAIC, NEW JERSEY.

CURTAIN-ROLLER.

1,149,993.

Specification of Letters Patent. Patented Aug. 10, 1915.

Application filed August 3, 1914. Serial No. 854,835.

To all whom it may concern:

Be it known that we, CYRUS L. BUNDY and WILLIAM GRANT, citizens of the United States, residing at East Orange, in the county of Essex, and Passaic, in the county of Passaic, New Jersey, respectively, have invented certain new and useful Improvements in Curtain-Rollers, of which the following is a specification.

10 The invention relates to curtain fixtures of that type wherein the spring-actuated roller is mounted in brackets within the window frame and is held at an adjusted height by shoes bearing frictionally against 15 the casing within guides provided for the purpose, the roller spring exerting a constant tension to elevate the curtain by rotating the roller.

In order that the roller spring shall at all 20 times be under sufficient tension as it lifts the curtain from its lowermost to its uppermost position, it is necessary that the spring shall be under some degree of tension even when the curtain is fully wound up and in 25 order to maintain the spring under tension while installing the curtain roller in its brackets it is usual to employ a pawl or other detent whereby to hold the spring, spindle and roller against relative movement until the spear head of the spindle is 30 safely engaged within its bracket and then in some manner to release such detent in order to allow the spring to exert its force on the roller; likewise to interengage the 35 spindle and roller before dismounting from the brackets so as to prevent unwinding of the spring when removed from the window for any purpose.

The primary object of the present invention 40 is the provision of an improved detent operating mechanism facilitating the engagement of the detent before the mounting of the curtain and providing for automatic reengagement when it is desired for any 45 reason to remove the curtain from the window.

In order that the invention may be readily understood a preferred embodiment of the same is set forth in the accompanying 50 drawing and in the subjoined detailed description based thereon. As, however, the invention is capable of embodiment in other and various constructional forms the drawing and description are to be taken in an 55 illustrative and not in an unnecessarily limiting sense.

In the drawing—Figure 1 is a side view of one end of a roller embodying the invention; Fig. 2 is a similar view partly in longitudinal vertical section; Fig. 3 is an end view with the detent disengaged; and Fig. 4 is an end view with the detent engaged.

In the drawings the reference numeral 11 designates the barrel of the roller within which is axially mounted the spindle 12 provided with the usual spear head 13 and connected with the barrel by means of a torsion spring 14. The spindle has its end bearing within the cylindrical flange 15 of an end plate 16 fitted within the end of the roller, 60 this general construction being well known in curtain rollers. Within one side of the spindle adjacent the spear head is a recess 17 which occupies a position within the plane of the depression of the end plate 16. 65

Adjacent that end of the roller within which is mounted the spindle 12 the roller shell is depressed longitudinally and transversely at 18 to accommodate a T-shaped lever 19 the T head 20 of which forms a 80 counterweight, the said lever being fulcrumed upon a pin 21 and having its outer end at 22 disposed within a slot of the end plate 16. Upon the end plate is pivoted at 23 a pawl 24 the tooth 25 of which is adapted to engage within the recess 17 of the spindle while the head of the pawl 26 normally rests against the arm 22 of the lever 19. 85

When installing the curtain roller the 90 spear head is rotated slightly with the curtain in an unwound condition and the pawl is then caused to engage within the recess by swinging the lever 19 upon its fulcrum either by engaging the counterweighted end 95 of the same with the finger or if the curtain be held with the lever on the lower side of the roller the counterweighted end 20 will act by gravity to operate the lever and press the pawl into the recess. The pawl having 100 once been engaged within the recess the curtain is then wound up and as the lever 19 is substantially flush with the roller surface the curtain overlies the said lever and holds the same out of engagement with the 105 pawl which retains its position within the recess by reason of the friction of the recess wall upon the pawl. The curtain roller is then placed in the window with the spear head 13 in engagement with its bracket and 110 with the recess on the lower side. If, now, the curtain be grasped and partially un-

wound the beveled surface 27 of the pawl tooth 25 will ride up on the wall of the recess and disengage the pawl. Thereafter in the operation of winding and unwinding 5 the curtain the pawl will be held out of the recess both by gravity and also by centrifugal action, and the action of the torsion spring 14 will be controlled solely by the frictional engagement of the shoes within 10 the guides of the window frame.

When it is desired to dismount the curtain from the window it will first be unwound to its full extent and as soon as the lever 19 is released from the restraint of the 15 curtain wound thereon it will drop by gravity to the position indicated in dotted lines in Fig. 2, pressing the pawl upward and causing its tooth 25 to engage within the recess of the spindle, thus locking the barrel 20 and spindle against relative rotation under the influence of the spring and permitting the curtain roller to be removed from its brackets without releasing the spring 14. Thereafter, as the spring is under full tension, 25 the curtain will be replaced within its brackets in an unwound condition and the spring will again be rendered operative by a slight unwinding movement causing the beveled surface 27 to ride upon the wall of the 30 recess as before described.

It will thus be seen that the invention provides not only mechanical means for engaging the pawl within the recess in the first instance, but means for automatically 35 reengaging the pawl and recess at any time when it is desired to remove the curtain roller from its brackets for any purpose, the configuration of the pawl itself providing for the disengagement of the same after in- 40 stallation.

We claim:

1. In a curtain roller, a barrel, a spindle therein adapted for engagement within supporting brackets, a torsion spring connecting 45 the barrel and spindle, normally inactive detent mechanism for locking the barrel and spindle against rotation under the influence of the spring, and means held inactive when the curtain is wound upon the roller and 50 acting when the curtain is unwound from the roller to cause interengagement of the detent mechanism.

2. In a curtain roller, a barrel, a spindle therein adapted for engagement within sup- 55 porting brackets, a torsion spring connect-

ing the barrel and spindle, the spindle provided with a recess and the barrel with a pawl for engagement therein, the pawl tending to avoid engagement with the recess, and pawl operating means for pressing the pawl 60 into engagement with the recess, said means held inactive when the curtain is wound upon the roller.

3. In a curtain roller, a barrel, a spindle therein adapted for engagement within supporting brackets, a torsion spring connecting the barrel and spindle, the spindle provided with a downwardly opening recess and the barrel with a pawl for engagement therein, the pawl tending under gravity to 70 avoid engagement with the recess, and pawl operating means tending to press the pawl into engagement with the recess, said means held inactive when the curtain is wound on the roller. 75

4. In a curtain roller, a barrel, a spindle therein adapted for engagement within supporting brackets, a torsion spring connecting the barrel and spindle, the spindle provided with a single downwardly opening recess and the barrel with a pawl for engagement therein, the pawl tending under gravity and centrifugal action to remain disengaged from the recess, and pawl operating means tending by gravity to press the pawl 80 into engagement with the recess, said means held inactive by the curtain when wound on the roller.

5. In a curtain roller, a barrel, a spindle therein adapted for engagement within supporting brackets, a torsion spring connecting the barrel and spindle, the spindle provided with a recess and the barrel with a pawl for engagement therein, the pawl tending under gravity and centrifugal action to 90 remain disengaged from the recess, and a counterweighted lever lying substantially flush with the roller surface and having its counterweighted arm underlying the curtain on the roller and its other arm disposed 100 adjacent the pawl, the lever held inactive by the curtain when wound on the roller and released and allowed to act on the pawl to press the same into the recess when the curtain is unwound.

CYRUS L. BUNDY.
WM. GRANT.
